(57) **CLAIM**

The ornamental design for a bottle, as shown and described.

DESCRIPTION

This application is related to co-pending application Ser. No. 29/453,035 filed Apr. 24, 2013, titled “Bottle” and to co-pending application Ser. No. 29/453,063 filed Apr. 24, 2013, titled “Bottle” and to co-pending application Ser. No. 29/455,626 filed May 22, 2013, titled “Bottle.”

FIG. 1 is a side view of a bottle, showing my new design.

FIG. 2 is a front view of a bottle, thereof.

FIG. 3 is a back view of a bottle, thereof; and,

FIG. 4 is a bottom view of a bottle, thereof.

The broken lines in FIGS. 1, 2 and 4 are included for the purpose of illustrating a portion of the bottle that forms no part of the claimed design.

The claimed bottle is used for storing cleaning fluids and cleaning small parts within.

1 Claim, 4 Drawing Sheets
